UNITED STATES PATENT OFFICE.

GUSTAF W. ELMEN, OF LEONIA, NEW JERSEY, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed August 17, 1921. Serial No. 493,146.

This invention relates to magnetic modulators and similar electromagnetic systems where it is desired to utilize the magnetic effect of a varying direct current upon an alternating current, and its object is to improve the efficiency and reliability of such devices.

The invention provides an improved magnetic system for such electromagnetic devices and makes use of a magnetic material characterized by high permeability and by low hysteresis losses.

Heretofore iron and silicon steel have been employed generally in electromagnetic devices in order to secure high permeability at the forces produced by the current passing therethrough, while the principal possible rivals of iron, nickel and cobalt, have found but little application due to their inferior magnetic characteristics. With nickel and cobalt in this respect, stands Heusler's alloy of aluminum, manganese and copper. It has been found that a composition of about two-thirds nickel and one-third copper, when tested at low magnetizing forces, gives a permeability higher than that of iron alone. It will be seen that with the exception of aluminum, all these metals stand close together in their atomic weights and atomic numbers, and in this specification these five elements, manganese, iron, cobalt, nickel, and copper, having these consecutive atomic numbers, 25, 26, 27, 28, 29, will be regarded as comprising the magnetic group of elements.

The criterion of high permeability is not the only one to be considered for seeking the best magnetic material for use in electromagnetic systems. If the magnetizing force and the resultant flux are changed rapidly, then for most purposes, the material should exhibit a low hysteresis loss. The development of eddy currents under these conditions may be obviated to a considerable extent by lamination; but the resistivity of the material is a factor that may be of importance in this connection; the higher the resistivity the more the eddy current losses will be kept down.

The description hereinafter given is made specific to the employment in a magnetic modulator of a new magnetic material comprising elements of the magnetic group combined in suitable proportions, which when

subjected to a proper heat treatment and guarded against undue stresses and other disturbing causes, develops and retains an extremely high permeability at low magnetizing forces and a low hysteresis loss.

Iron and nickel are fused together in an induction furnace in the proportions of about 21½% iron and 78½% nickel. Good commercial grades of these metals are suitable for this purpose. The molten composition is poured into a mold and cooled either in the form in which it is ultimately to be used or in a convenient form to be worked over for that purpose. In the latter case it may be swaged, drawn, or rolled. When desired to be laminated, some such manner of working the material to the required form may be necessary.

While 78½% and 21½% have been mentioned as giving the proportion of the ingredients, nickel and iron, to be employed in making up the improved magnetic material, it will be understood that the proportion may deviate considerably from these figures when nickel and iron are the only ingredients, and that when there are other ingredients, this proportion may not apply. Up to the present time when the only ingredients are nickel and iron, it has been found that a proportion about the same as that named, gives the greatest permeability for low magnetizing forces. Other ingredients than nickel and iron may be employed for various purposes, not only to confer high permeability on the product, but for other objects; for example, it may be desirable to add chromium for the reason that a comparatively small quantity of this element will cause a decided increase in the resistivity of the composition, and this high resistivity may be a desirable factor to cut down the eddy current losses in the magnetic material. A composition of nickel 55%, iron 34%, and chromium 11%, has been carefully prepared, heat-treated and tested, and has been found to give a high value of permeability at low magnetizing forces.

To develop the utmost permeability in the magnetic material the cores may be subjected to a heat treatment, the treatment required in any particular case varying somewhat as regards temperatures employed and duration of heating and cooling. The opti-

mum values of these variables may be readily determined in any specific case by experiment. A suitable heat treatment to develop high permeability has been found to be to heat the material to a temperature that will be suitable for annealing, then to cool at an optimum rate that must be determined by experiment. After the heat treatment, the material must be guarded against any considerable strains, in other words, the heat treatment is applied to the material in a form ready for assembly in the apparatus in which it is to be used.

Referring to the drawings:

Fig. 1 shows one type of a magnetic modulator.

Figs. 2, 3 and 4 show curves useful in describing the operation thereof.

Referring to Fig. 1, 4 represents a radio frequency alternator, which is connected to a coil 5 located on one part of a core 6. The current flowing through this circuit will be referred to as I_1 and the circuit itself as C_1 . A coil 7, which is also located on the core 6, is connected to an antenna 8 and to a coil 9 located on a magnetic core 10 and thence to ground. The current in this circuit will be hereinafter referred to as I_2 and the circuit itself as C_2 . A coil 11 located on the core 10 is connected through choke coils 12 and 13 to telephone transmitter 14 and battery 15. The current in this circuit will be hereinafter referred to as I_3 and the circuit itself as C_3 . In the usual construction of this type of modulator the cores 6 and 10 are made of iron.

Now, when the circuit C_1 is closed, the current I_1 flowing through the coil 5 produces a certain magnetizing force which produces lines of magnetic induction in said core. These lines of force, in cutting the coil 7, set up therein an electromotive force, the value of which will be dependent upon the lines of magnetic induction flowing in the core. The current I_2 , in passing through coil 9, produces a magnetizing force which causes lines of flux to be set up in the core 10. These lines of flux will not cause current to flow through coil 11 when C_3 is closed on account of the choke coils 12 and 13. The closing of C_3 results in sending current I_3 through the coil 11, and this coil effects a change in the current I_2 flowing in the circuit C_2 .

Referring to Fig. 2, the effect of the direct current I_3 upon the alternating current I_2 is shown. The ordinates of this figure represent the permeability to the alternating current at a magnetizing force of about $H=0.1$ c. g. s. units, and the abscissæ represent the magnetizing force produced by the direct current. The curve A shows this relation for soft iron, and curve B for a nickel-iron composition containing approximately 78½% nickel and 21½% iron.

With no direct current passing the soft iron exhibits a permeability to the alternating current producing a magnetizing force of $H=0.1$ c. g. s. units, of about 250, while the nickel-iron composition exhibits a permeability of about 5,000. Now, if a rather small amount of direct current is passed, the permeability to the alternating current is increased somewhat, much more in the case of the nickel-iron composition than with the soft iron. A point is reached, however, when the permeability begins to decrease with an increase of direct current, the change being rather gradual in the case of soft iron and rather abrupt in the case of the nickel iron composition. It is this change in permeability at low magnetizing forces to alternating currents, which is affected by varying the direct current that is essential in the operation of the magnetic modulator. Usually sufficient direct current is employed so that the change will fall along the part of the curves where the permeability to the alternating current decreases with an increase in direct current. The following description will be made specific to this general practice.

Assuming that the circuit C_2 has no capacity therein, the inductance in the circuit is determined by the two currents I_1 and I_3 and the current in circuit C_2 may be readily ascertained from a curve such as that shown in Fig. 3. The ordinates of this curve represent the current in circuit C_2 , and the abscissæ represent the corresponding inductance values in circuit C_2 . It will be seen from this curve that an increase in the inductance produces a decrease in the current, and a decrease in the inductance produces an increase in the current. Now the effect of interposing capacity in circuit C_2 is to change the simple relation between the current and the inductance to that shown by the curve in Fig. 4. This curve is obtained from the expression

$$E = I \sqrt{L^2 \omega^2 + R^2} - \frac{1}{C^2 \omega^2}$$

in which—

E =the electromotive force in C_2 ;

I =the current in C_2 ;

L =the inductance in C_2 ;

$\omega=2\pi+\text{the frequency of the current in } C_2$;

R =the resistance of C_2 , and

C =the capacity of C_2 .

The assumption is made, plotting the curve of Fig. 4, that the resistance in the circuit is negligible. The curves of Figs. 3 and 4 represent the relative change of inductance with current for a nickel-iron composition containing approximately 78½% nickel and 21½% iron.

In the operation of the magnetic modulator, circuit C_2 is tuned with a certain amount of direct current flowing through circuit C_3 .

This circuit is tuned so that the maximum current which can flow therethrough is represented by the maximum point 16 in the curve of Fig. 4, the current flowing through 5 C_3 being constant. It will be apparent from this curve that either an increase or decrease in I_3 caused by the operation of the transmitter 14 will cause the inductance in C_2 to decrease, resulting in a detuning of 10 the circuit.

The effectiveness of a modulator of this type is measured by the relative change in the current I_2 for a variation in the direct current I_3 . It is desirable that a maximum 15 change be secured in I_2 for a relatively small change in I_3 .

The great advantage to be secured in utilizing the nickel-iron compositions over that obtained when iron is employed, is shown 20 by a consideration of Fig. 2. In the first place, the nickel-iron compositions have a much higher permeability at low magnetizing forces than iron, which fact will permit the use of a much smaller transformer core 25 than would be required in the case of iron, and still retain the desired permeability; or if desired, the core may be made of the same size as the iron core in use at the present time, and a higher inductance obtained than 30 has been possible formerly. In the second place, a comparatively small change in the value of the direct current flowing in circuit C_3 will result in an exceedingly large change in the permeability to the alternating 35 current I_2 , and this fact will permit a great saving in the energy consumed in the operation of the device. In the third place, the rate of change of permeability to the alternating current and the magnetizing force produced by the direct current is considerably greater in the case of the nickel-iron 40 compositions, and this will permit a much better control of the radio frequency current.

When iron is employed in the core 10, it is necessary to use extremely thin sheets in order to reduce the eddy current losses therein. The extremely high specific resistance of the nickel-iron compositions, however, will warrant the use of much thicker 50 sheets and therefore effect a great saving in the expense of constructing the core.

It has been found that the nickel-iron compositions possess a much smaller hysteresis 55 loss than iron and this characteristic further accentuates the advantages to be secured from the use of the iron-nickel compositions as a core material.

While one particular nickel-iron composition 60 has been referred to as a basis of comparison with iron, it is not intended to restrict the scope of this invention to this particular composition, but it is to be understood that all such nickel-iron compositions 65 which exhibit the magnetic properties here-

inabove mentioned, are considered to be within the scope of the appended claims.

Although the magnetic modulator for use in radio telephony has been described more particularly as one embodiment of the invention, it is not intended to limit the invention thereto. Other magnetic devices which comprise an alternating current circuit and a direct current circuit, may also be provided with the magnetic material of the invention with beneficial results.

What is claimed is:

1. A magnetic circuit, two electric circuits interlinked therewith, means to pass variable currents of high and low periodicity in said electric circuits, respectively, said magnetic circuit being of relatively high permeability at low magnetizing forces whereby slight variations of the low periodicity current produce large variations of the high periodicity current.

2. An electromagnetic device comprising an alternating current circuit and a direct current circuit, and having a magnetic material comprising two elements of the magnetic group.

3. An electromagnetic device comprising an alternating current circuit and a direct current circuit, and having a magnetic material comprising nickel and another member of the magnetic group.

4. An electromagnetic device comprising an alternating current circuit and a direct current circuit, and having a magnetic material comprising nickel and iron.

5. A magnetic modulator having a magnetic material comprising two elements of the magnetic group and having a permeability higher than that of iron at low magnetizing forces.

6. A magnetic modulator having a magnetic material comprising nickel and another element of the magnetic group, the nickel component predominating and the material having a permeability higher than that of iron at low magnetizing forces.

7. A magnetic modulator having a magnetic material comprising nickel and iron in which the nickel component predominates and having a permeability higher than that of iron at low magnetizing forces of the order of a few tenths of a gauss.

8. A magnetic modulator comprising a magnetic material approximately 78½ per cent nickel and 21½ per cent iron.

9. The combination of an alternating current circuit, a direct current circuit and a magnetic circuit inductively related to said circuits and composed of a material containing nickel and iron, said material being so treated that its permeability at low magnetizing forces is higher than that of iron.

10. The combination of an alternating current circuit, a direct current circuit and a magnetic circuit inductively related to said

circuits and composed of a material containing nickel and iron, said material at low magnetizing forces having a permeability which is higher than that of iron and which changes rapidly with small changes in the magnetizing force.

11. The combination of an alternating current circuit, a direct current circuit and a magnetic circuit inductively related to said circuits and composed of a material containing nickel and iron, said material at low magnetizing forces having a higher permeability than iron and having the additional property of changing its permeability more rapidly than iron in response to small changes in the magnetizing force applied.

12. The method of varying the permeability of a composition comprising two elements of the magnetic group to alternating currents producing low magnetizing forces which comprise subjecting said composition to the influence of a varying direct current.

13. The method of varying the permeability of a composition comprising nickel and another member of the magnetic group, to alternating currents producing low magnetizing forces, which comprises subjecting said composition to the influence of a varying direct current.

14. The method of varying the permeability of a nickel-iron composition to alternating currents producing low magnetizing forces, which comprises subjecting said composition to the influence of a varying direct current.

15. In a magnetic circuit subject to a composite magnetizing force from a direct current circuit, and an alternating current circuit interlinked with said magnetic circuit, the method of operating efficiently which consists in creating a large magnetic flux in the magnetic circuit by means of a small direct current magnetizing force.

16. An electromagnetic device comprising

a magnetic core consisting chiefly of nickel and iron, means for subjecting said core to a direct current flux, and additional means for superimposing an alternating current flux on said core.

17. An electromagnetic device comprising a core composed of a material having a permeability higher than that of iron at low magnetizing forces, means for subjecting said core to a constant flux, and additional means for simultaneously subjecting said core to a varying flux.

18. An electromagnetic device comprising a core composed of a nickel-iron alloy in which the nickel component predominates and having a permeability higher than that of iron at low magnetizing forces of the order of a few tenths of a gauss, means for subjecting said core to a constant flux, and additional means for simultaneously subjecting said core to a varying flux.

19. An electromagnetic device comprising a magnetic core consisting chiefly of nickel and iron, means for subjecting said core to a varying magnetizing force of high frequency, and additional means for simultaneously subjecting said core to a varying magnetizing force of low frequency.

20. An electromagnetic device having a magnetic core composed of a nickel iron alloy in which the nickel component predominates, and having a permeability higher than that of iron when subjected to an alternating magnetizing force of low value, said permeability changing much more rapidly than that of iron when the core is simultaneously subjected to small variations in a superimposed direct current magnetizing force.

In witness whereof, I hereunto subscribe my name this 10th day of August, A. D., 1921.

GUSTAF W. ELMEN.
